NOZZLE BURNER

James K. Clark, New Hartford, N. Y., assignor to
The Partlow Corporation, a corporation of New
York

Application December 9, 1947, Serial No. 790,532

4 Claims. (Cl. 158—115)

1

My invention relates generally to safety gas burners and in particular to a nozzle burner which combines the pilot flame and the main burner flame.

In prior gas burners, it has been customary to use a separate pilot flame for igniting the main gas burner. I have discovered that the separate pilot flame is a constant source of annoyance and potential hazard. In these prior gas burners, air currents can blow the pilot flame away from the main burner so as to cause the ignition of the main burner to be delayed or even entirely prevent ignition of the main burner. It has also been discovered that waving of the pilot flame will break the electrical flame circuit in a flame conductivity type of flame failure protective device and thereby cause a premature shut-down of the main burner.

Another disadvantage in the previous devices is that slight clogging or stoppage in the pilot burner, which will cause the pilot flame to be shortened, may break the electrical flame circuit and cause a shut-down of the appliance. With these conditions, the burner devices are not entirely safe, even though a flame failure protective device is used. I have discovered that the gas burner is much safer when the electrical flame circuit of the flame conductivity type flame failure protective device is so placed as to contact both the main burner flame and the pilot flame. In the prior construction of the burners, this was impractical if not altogether impossible.

With these views in mind, I specify that one of the objects of my invention is to make the pilot burner a part of the main burner.

Another object of my invention is to provide a pilot burner associated with the main burner in such manner that the pilot flame will not be blown away from the main burner flame.

Another object of my invention is to provide a main burner member for projecting combustible fuel into a combustion area and a shell member surrounding the said main burner member for projecting pilot combustible fuel on the periphery of the combustion area.

A further object of my invention is to provide a pilot burner for projecting combustible fuel on the periphery of the main combustion area of the main burner.

A further object of my invention is to provide an electrode contacting both the pilot flame and the main burner flame to establish an electrical flame circuit through either or both of these flames.

As a still further object of my invention, I pro-

vide a pilot burner for projecting combustible fuel into the periphery of the combustion area of the main burner to prevent the main burner flame from lifting or traveling away from the main burner.

Other objects and a fuller understanding of my invention may be had by referring to the following description and claims, taken in conjunction with the accompanying drawings, in which:

10 Figure 1 of my drawings is a diagrammatic representation of my new nozzle burner as connected to a fuel supply and controlled by flame failure protective device;

15 Figure 2 is a cross-sectional view of my new nozzle burner to better illustrate the construction thereof; and,

Figure 3 is an end view of my nozzle burner.

In Figure 1 of my drawings, I have designated my new, useful and improved nozzle burner by the number 10. This nozzle burner 10 includes a main burner 11 and a pilot burner 12, as is indicated in Figure 2. A flame protective control device 13, illustrated in Figure 1, insures safe operation of my burner device. The main burner

20 11 is connected to a source of combustible fuel by the fuel line 14. Similarly, the pilot burner 12 is connected to the source of combustible fuel by fuel line 15. Each of these fuel lines 14 and 15 have suitable air mixture devices 18 and 19, respectively. A main burner valve 16 in the fuel line

25 14 to the main burner is controlled and operated by the flame protective control device 13 to control the admittance of combustible fuel to the main burner 11. Similarly, a pilot burner valve 17 connected in the fuel line 15 to the pilot burner is

30 35 operated by the flame protective control device 13 to control the admittance of combustible fuel to the pilot burner 12. The flame protective control device 13 may be of any suitable construction commonly used for insuring safe opera-

40 45 tion of a burner device.

The preferred construction of my new and improved nozzle burner 10 is best illustrated in Figure 2 of my drawings. The main burner 11 is constructed with a hollow support body 22 with a flange 23 on one end thereof and the main burner tube 24 extending from the other end thereof. The main burner tube 24 has a flange

50 55 23 at the outer end thereof. This main burner tube 24 is pressed into the hollow support body 22 and engages the stop shoulder 25 and the support surface 26. The stop shoulder 25 limits the pressed movement of the main burner tube 24 into the hollow support body 22. The support surface 26 engages the main burner tube to fric-

tionally hold it in the hollow support body 22. I have found it advisable to provide this main burner tube 24 with a nozzle 27 to provide an orifice or port at the end thereof. This nozzle 27 is preferably supported on the end of the main burner tube 24 by bolting the nozzle 27 to a ring flange 29 with bolts 28. The fuel line 14 to the main burner 11 is threaded into the hollow support body 22. Combustible fuel passes from this fuel line 14 through the hollow support body 22 and into the main burner tube 24. The nozzle 27 at the end of the main burner tube 24 directs the combustible fuel through the port or orifice and into a main combustible area externally of the main burner 11 where the combustible fuel burns as a flame.

In my nozzle burner the pilot burner projects combustible fuel at spaced locations on the periphery of this combustion area. I have provided a shell member 32 concentrically spaced about the main burner tube 24. In my preferred design, this shell member 32 is also supported by the hollow support body 22 and extends beyond the nozzle 27 of the main burner tube 24. When the main burner tube and the shell member are built into a burner device as the component part thereof, the main burner tube 24 may be referred to as an inner tube and the shell member as an outer tube.

The shell member 32 surrounds, and is spaced from the nozzle 27 to provide an annular space therebetween. A pilot burner screen 33, preferably constructed of a corrugated strip of material, may be placed in this annular space between the shell member 32 and the nozzle 27. When the shell member 32 is concentrically spaced from the nozzle 27 the pilot flame will be a concentric annular ring of flame on the periphery of the main combustion area.

In my preferred design of my nozzle burner, as illustrated in the drawings, the hollow support body 22 has an enlarged portion 34 which extends about the main burner tube 24. The enlarged portion 34 has a shoulder 35 and a support surface 36. The shell member 32 is pressed into this enlarged portion 34 until the end of the shell member 32 engages the stop shoulder 35. The support surface 36 frictionally engages the outer surface of the shell member 32 to prevent the shell member 32 from falling out of the enlarged portion 34 of the hollow support body 22.

I have further provided this enlarged portion 34 with a hollow cavity 37 extending internally thereabout. The fuel line to the pilot burner is threaded into this enlarged portion 35 to inject combustible fuel into this hollow annular cavity 37. The combustible fuel encircles the main burner tube 24 within this hollow cavity 37 and passes therefrom along the space between the shell member 32 and the main burner tube 24. After the combustible pilot fuel is forced through the pilot burner screen 33 it burns on the periphery of the main combustion area as a pilot ring encircling the main burner flame.

A conductor rod 40 extends longitudinally of the main burner tube 24 and is disposed axially therein. This conductor rod 40 has an electrode 41 which extends through the nozzle 27 and into the combustion area at the end of the main burner. The electrode 41 is disposed to provide an electrical circuit path through either the main flame or through the pilot flame. This electrical flame path extends from the electrode 41 to the shell member 32 or to the bolts 28 which hold the nozzle 27 on the end of the main burner

tube 24. The main burner tube 24 and the shell member 32 are electrically connected together by means of the hollow support body 22. This hollow support body 22 is at ground potential as indicated by the symbol 39.

The conductor rod 40 is supported by an insulation support member 42 which engages the inside of the flange 29 on the end of the hollow support body 22. A support ring 43 is bolted to this flange 29 by bolts 44. When the support ring is drawn against the flange 29 the insulation support member 42 is locked in place. A peripheral portion 47 of the insulation support member 42 extends between the support ring 43 and the flange 29. An end cap 45 may also be held onto this support ring 43 by the bolts 44 to enclose electrical connections onto the conductor rod 40 and also to enclose the insulation support member 42. The electrical conductor rod 40 is electrically connected by an electric cable 46 to the control device 13. This electric cable 46 may be fastened by bolt and nut means or by other suitable electrical fastenings to the conductor rod 40. In Figure 1 of my drawings, I have illustrated the control device 13 as being grounded symbolically as represented by the number 48.

The electrical circuit may be traced from the control device 13 through the cable 46, the conductor rod 40 and into the electrode 41. When the nozzle burner has a flame at the end thereof in the combustion area or a pilot flame in the periphery of the combustion area, this flame will provide an electric circuit between the electrode 41 and the bolt 28 connected to the main burner tube 24 or the shell member 32. From the main burner tube 24 or the shell member 32 the electrical circuit may be traced through the hollow support body 22 to the ground 39 hence through the ground 48 back to the control device 13. To light the burners, the combustible fuel emitting from the pilot burner into the periphery of the main combustion area is ignited by a spark between the electrode 41 and the shell 32. After the pilot flame has been ignited the control device 45 responds to the change of conductivity between the electrode 41 and the shell 32 or the bolt 28 caused by the pilot flame and opens the valve 16 to admit combustible fuel to the main burner. I have discovered that using a ring pilot flame insures immediate ignition of the burner combustible fuel in the combustion area. Should the main burner and the pilot flame both go out the control device will automatically shut the valves 16 and 17 to prevent combustible fuel unsafely emitting into the air.

I have also discovered that the pilot ring flame on the periphery of the main combustion area will prevent the main flame from lifting or moving away from the main burner tube. This moving away of the flame is due to the time required in igniting the combustible fuel after it leaves the end of the main burner tube. The pilot ring of flame insures immediate igniting of the combustible fuel and thus keeps the main flame on the end of the main burner tube.

Although I have described my invention in its preferred form with a certain degree of particularity, it is understood that the present disclosure of the preferred form has been made only by way of example and that numerous changes in the details of construction and the combination and arrangement of parts may be resorted to without departing from the spirit and the scope 75 of the invention as hereinafter claimed.

What is claimed is:

1. A burner, comprising a hollow body having an axis and a nozzle end, a nozzle in said nozzle end having a wall defining a concentric restricted nozzle opening, a conductor rod insulatively carried coaxial with said body, a main fuel supply line connected to the interior of said hollow body, a pilot shell carried by said hollow body concentrically surrounding and spaced from said hollow body, said shell having a flame end extending past said nozzle and substantially surrounding the periphery thereof to define with said nozzle a combustion area adjacent said nozzle, a pilot supply line connected to said hollow body and communicating with the space between said shell and said body, whereby a pilot flame will be established as a substantially annular wall of flame adjacent said shell at said flame end within said combustion area, said conductor rod extending coaxially through said nozzle opening and having a terminal end establishing a gap with one of said shell and said body, which gap is in said combustion area.

2. A burner, comprising a hollow cylindrical body having a nozzle end, a nozzle in said nozzle end having a wall defining a concentric restricted nozzle opening, a conductor rod insulatively carried coaxial with said body, a main fuel supply line connected to the interior of said hollow body, a pilot shell carried by said hollow body concentrically surrounding and spaced from said hollow body, said shell having a flame end extending past said nozzle and substantially surrounding the periphery thereof to define with said nozzle a partially enclosed combustion area, a pilot supply line connected to said hollow body and communicating with the space between said shell and said body, whereby a pilot flame will be established as an annular wall of flame adjacent said shell at said flame end within said combustion area, said conductor rod extending coaxially through said nozzle opening and having a terminal end in said combustion area, and said terminal end bending toward said shell to provide a gap therebetween.

3. A burner, comprising a hollow cylindrical body having a nozzle end, a nozzle in said nozzle end having a wall defining a concentric restricted nozzle opening, a conductor rod insulatively carried coaxial with said body, a main fuel supply line connected to the interior of said hollow body, a pilot shell carried by said hollow body concentrically surrounding and spaced from said hollow body, said shell having a flame end extending past said nozzle and completely surrounding the periphery thereof to define with said nozzle a cup-like combustion area, a pilot supply line connected to said hollow body and communicating with the space between said shell and said body, means for supplying a mixture of fuel and oxygen to said pilot supply line, a pilot burner screen extending peripherally about said nozzle between said nozzle and said shell and separating said combustion area from the space

between said shell and said hollow body, whereby a pilot flame will be established as an annular wall of flame adjacent said shell at said flame end within said combustion area, said conductor rod extending coaxially through said nozzle opening and having a terminal end in said combustion area, and said terminal end bending toward said shell to provide a gap therebetween less than the spacing between said conductor rod and the wall of said nozzle opening with said gap being disposed at said annular wall of flame.

4. A burner, comprising a hollow cylindrical body having a nozzle end and an open end, a nozzle in said nozzle end having a wall defining a concentric restricted nozzle opening, an insulator closing said open end, a conductor rod carried by said insulator coaxial with said body, a main supply line connected to the interior of said hollow body, means for supplying a mixture of fuel and oxygen to said main supply line, a pilot shell carried by said hollow body concentrically surrounding and spaced from said hollow body, an annular chamber in said hollow body separate from the interior thereof, the space between said shell and said body communicating with said annular chamber, said shell having a flame and extending past said nozzle and completely surrounding the periphery thereof to define with said nozzle a cup-like combustion area, a pilot supply line connected to said hollow body and communicating with said annular chamber, means for supplying a mixture of fuel and oxygen to said pilot supply line, a pilot burner screen extending peripherally about said nozzle between said nozzle and said shell and separating said combustion area from the space between said shell and said hollow body, whereby a pilot flame will be established as an annular wall of flame adjacent said shell at said flame end within said combustion area, said conductor rod extending coaxially through said nozzle opening and having a terminal end in said combustion area, and said terminal end bending toward said shell to provide a gap therebetween less than the spacing between said conductor rod and the wall of said nozzle opening with said gap being disposed at said annular wall of flame.
